UNITED STATES PATENT OFFICE

2,613,917

TURBINE-IMPACT DRILL

William R. Postlewaite, Menlo Park, Calif., assignor, by mesne assignments, of one-half to California Research Corporation, San Francisco, Calif., a corporation of Delaware, and one-half to A. O. Smith Corporation, Milwaukee, Wis., a corporation of New York

Application April 14, 1948, Serial No. 21,083

1 Claim. (Cl. 255—4.4)

1

This invention relates to the art of deep well drilling and particularly to that in which a prime mover, which may be an axial flow turbine, is placed at the lower end of a string of pipe or conduit and is actuated by the drilling fluid pumped downwardly through the conduit, the latter transmitting the required reactive torque to control equipment at the surface and being lowered progressively thereby as the drill cuts away the formations encountered.

Heretofore, such turbine drills, for example, those of the United States patents to C. C. Scharpenberg No. 1,482,702, issued February 5, 1924, and to Lloyd Yost No. 2,348,047, issued May 2, 1944, have utilized the simple rotation set up in the axial shaft which is turned by appropriately inclined turbine blades or vanes. This invention is intended to provide additional means for imparting periodically a sharp downward blow or impact to the rotating drill bit, to facilitate its penetration into very hard formations.

One arrangement for imparting impact to a conventional drill bit rotated by means of a hollow shaft driven from motive power at the surface is that of the United States Patent No. 2,425,012, issued August 5, 1947 to R. E. Snyder. That device utilizes a drag member designed to be restrained only by the drilling fluid and thus to provide relative rotation to cooperating cams which lift an annular hammer to impart periodically a downward shock or impact to the drill bit. Such an arrangement has the disadvantage of lack of positive means for restraining one of the cams, which is overcome by the combination which will be described below.

The present invention is directed broadly to the combination of a hollow pipe or conduit which extends downwardly from the surface to a prime mover, desirably a drilling fluid-driven turbine element having a housing secured to the conduit and in which there rotates a shaft carrying a drill bit of any desired type. A weight member or hammer, desirably surrounding the shaft above the bit, is keyed or otherwise slidably secured to the housing, and lifting means such as an inclined cam face are provided on the shaft which cooperate with corresponding means on the hammer to lift the latter due to the shaft rotation and permit it to drop again to impart the impact or shock to the drill bit. Desirably, but not necessarily, a spring between the housing and the sliding weight may be provided to urge the latter downwardly and increase the sharpness of the blow and thus permit higher rotative speeds without undue time-lag between

2

the release of the hammer and its impact against the bit structure. It is also desirable that the turbine thrust bearing be of a type adapted to absorb the periodic impacts generated by the hammer mechanism.

An alternative to the shock absorbing type of thrust bearing arrangement is an elongated drill collar which may be splined to the lower end of the turbine shaft and mounted above the rotation restraining means of the impact hammer and lower shaft to which the drill bit may be secured. This permits using rigid types of thrust bearings in the turbine mechanism.

It is an object of this invention to provide a combination of a prime mover located adjacent the bottom of a relatively stationary conduit, which may be drill pipe extending from the top of a well bore, to rotate a shaft carrying a cam which is adapted to cooperate with a second cam slidably secured to the lower end of the prime mover housing so as to lift and release periodically a weight or hammer member and impart impact to a drill bit at the lower end of the entire assembly.

Another object is to provide a combination of a turbine drill of the nature described with an impact mechanism so that the latter will be positively actuated at least once each revolution of the turbine shaft.

Another object is to provide an arrangement of the type described in which the dead weight or load on the bit due to gravity may be controlled, as by a predetermined length of drill collar and on which may be superimposed a periodic impact effect due to an annular hammer actuated by the rotation of the turbine shaft relative to the turbine housing.

These and other objects and advantages will be further apparent from the following description of a preferred embodiment of the invention together with certain alternatives, and from the accompanying drawings which form a part of this specification and illustrate typical constructions embodying the invention.

In the drawings, Figure 1 is a longitudinal sectional view of a well drilling tool embodying this invention.

Figure 2 is a transverse sectional view on line II—II of the arrangement shown in Figure 1.

Figure 3 is a side elevational view of a part of the arrangement of Figure 1 showing the slideable weight and cam in position to deliver an impact to a drill bit (not shown).

Figure 4 is a longitudinal sectional view of an alternative arrangement to that of Figure 1 in

which a drill collar is positioned within the lower end of the housing below the turbine elements to control the weight on the drill bit.

Figure 5 is a transverse sectional view on line V—V of the arrangement of Figure 4.

Figure 6 is a transverse sectional view on line VI—VI of the arrangement of Figure 4.

Referring to the drawing and particularly to Figure 1, reference numeral 10 illustrates a prime mover housing at the lower end of a relatively stationary pipe or conduit which extends to the top of the well bore and is suitably supported there by the usual hoisting means (not shown) such as are used for deep well drilling. In this example, drilling fluid is supplied to the upper end of the conduit and flows downwardly therethrough to a turbine element which may be that of the Scharpenberg Patent No. 1,482,702 or the Yost Patent No. 2,348,047. The lower end of the driven shaft of the turbine element is desirably coaxial with housing 10 and is designated by reference number 11. Shaft 11 is preferably hollow as at 12 to conduct the drilling fluid, which forms the motive power for the turbine or prime mover, downwardly to the drill bit which will be described below.

In order to absorb the shock or impact developed by means which will be described below to prevent wear or damage to the turbine elements, it is desirable to provide thrust bearing sleeves 13 which may be suitably secured within housing 10, and corresponding rings 14 on turbine shaft 11, with intermediate resilient members 15, which may be rubber, neoprene or the like, secured to the top and bottom faces of rings 14. To maintain the axial alignment of shaft 11 within housing 10, renewable bearing sleeve 16 secured within housing 10 and shaft sleeve 17 may be mounted as shown, with a hardened face member 18 on sleeve 17 adapted to bear against a resilient sleeve member 19, which may also be rubber, neoprene or the like. In the arrangement shown, a threaded retainer 20 is adapted to be received within housing 10 to hold sleeves 13 and 16 within the housing.

At the lower end of shaft 11 is an anvil member 21, in this example connected to the shaft by a threaded joint 22. If desired, anvil 21 could be made integral with the shaft. Anvil 21 also serves as a sub to which drill bit 23 may be secured by the threaded connection 24. Bit 23 is provided with the usual central passage 25 which receives the drilling fluid from the lower end of passage 12 of shaft 11 to conduct it to the eyes of the bit in the usual manner.

Surrounding that portion of shaft 11 which extends below housing 10 is an annular hammer or weight 26, provided with an enlarged bore 27 at the upper and lower ends of which are guide lugs 28 and 29 (Figure 2). The upper end of hammer 26 is desirably reduced in diameter to be received for a short distance within the lower end of housing 10 and is prevented from rotation therein by means of longitudinal keys 30 welded or otherwise secured to the hammer and adapted to move longitudinally within slots 31 (Figure 3) in the housing. By the means just described, hammer 26 is permitted to move longitudinally with respect to the lower end of shaft 11 and is positively prevented from rotating with the shaft by the inter-engagement of keys 30 in slots 31 of the housing 10.

In this example the lifting and releasing or dropping function of hammer 26 is provided by an inclined cam face 32 at the upper end of anvil 21 which cooperates with a correspondingly

formed cam face 33 at the lower end of hammer 26. When shaft 11 carrying anvil 21 rotates as shown by the arrow of Figure 3, the cooperating faces 32 and 33 will cause hammer 26 to be lifted until the vertical steps 34 and 35 on anvil 21 and hammer 26, respectively, reach the position shown in that figure, whereupon the hammer will be released to be dropped against the anvil to give an impact to it and to drill bit 23. Desirably but not necessarily the effective impact may be increased and the hammer travel time decreased by a spring 36 which, in this example, is placed between the upper face of hammer 26 and a guide bushing 37 within housing 10. Drilling fluid is vented through ports 38.

The alternative arrangement of Figure 4 illustrates the upper end only of a modification in which the lower end of shaft 11 from the turbine element or prime mover, which could be that of the Scharpenberg or Yost patents referred to above, is splined as at 40 within a hollow connecting member 41. Shaft 11 enters member 41 through a guide bore 42 which is desirably sealed as at 43. Vents 44 permit the drilling fluid which is used as motive power for the turbine element, to pass freely into and out of shaft 11, depending upon the longitudinal position of the splined portion 40 in connecting member 41.

The lower end of member 41 is connected to an elongated heavy weight member 45, commonly designated a drill collar, by means of a threaded connection 46. In the arrangement shown, turbine housing 10 is extended downwardly to enclose the full length of drill collar 45, the latter being centered in the housing by rubber guide bearings 47 which are desirably longitudinally slotted in the conventional manner as at 48. A second shaft 49 extends downwardly from the lower end of drill collar 45 through a hammer or weight member 26, the lower end of which is provided with a cam face 32 as in Figure 1, to an anvil member 21 having a corresponding cam face 33 and drill bit 23 (not shown).

The primary purpose of the alternative of Figure 4 is to permit substantial longitudinal motion of the assembly comprising member 41, drill collar 45, shaft 49, anvil 21 and drill bit 23 with respect to the turbine shaft 11 and housing 10. Accordingly, the longitudinal slots at the lower end of housing 10 which are engaged by the rotation-preventing means for hammer 26 are correspondingly elongated as at 50 310 to accommodate keys 300 (Figure 4).

In conclusion, it will be appreciated that this invention comprehends broadly a combination of elements particularly adapted to be connected to the lower end of a pipe or conduit extending from the surface of a drilling well, with a prime mover, which may be a mud driven turbine, adjacent the lower end of the casing to rotate a drill bit, the particularly novel features including an impact hammer or weight with inclined faces or analogous means to be lifted by the relative rotation of the drill bit with respect to the prime mover housing to impart periodic downward impact to the bit and thus facilitate removal of hard or brittle rock formations. Although specific embodiments of this arrangement have been described and illustrated, it is obvious that numerous changes could be made therein without departing from the invention, and all such modifications and changes that come

within the scope of the appended claim are intended to be embraced thereby.

I claim:

In a rotary-impact well drilling tool adapted to be positioned at the lower end of a conduit extending downwardly from the surface and including a prime mover adjacent the lower end of the conduit having a housing connected to said conduit and a downwardly extending rotatable shaft concentric therewith, the combination comprising an elongated drill collar connected to said shaft and splined therewith to be longitudinally movable, a second concentric shaft below said drill collar and rotated thereby, the lower end of said second shaft adapted to receive a drill bit, a weight slidably and rotatably mounted on said second shaft, longitudinally movable means connecting said housing and said weight for restraining said weight from rotation relative to said housing, an inclined

5
